UNITED STATES PATENT OFFICE

EDWIN G. HINES, OF DRUMS, PENNSYLVANIA

INSULATED BOTTLE RECEPTACLE

Application filed August 24, 1927. Serial No. 215,230.

This invention relates to special receptacles and more particularly to a receptacle to receive a milk bottle and may, therefore, be referred to as a bottle cabinet.

5 One object of the invention is to provide a receptacle of this character having its body and cover insulated to exclude heat and cold so that when a bottle of milk is placed in the cabinet it will not be liable to freeze in cold 10 weather or become sour during hot weather.

Another object of the invention is to provide the cabinet with a liner spaced from the body of the cabinet by the insulation and removable so that it may be thoroughly cleaned 15 and the insulation repaired or renewed when necessary.

Another object of the invention is to form the insulation of sheets disposed against the bottom and the walls of the body, the sheets 20 of insulation which fit against the walls of the body carrying vertically disposed strips which retain the walls of the liner spaced from the insulating sheets to define dead-air spaces and also constitutes skids to facilitate 25 insertion and removal of the liner.

Another object of the invention is to so form the body that it may be cheaply produced and easily secured against a wall or other support.

30 The invention is illustrated in the accompanying drawing, wherein

Figure 1 is a view showing the improved bottle receptacle in front elevation;

Fig. 2 is a vertical sectional view through 35 the receptacle taken on the line 2—2 of Fig. 1, and

Fig. 3 is a transverse sectional view taken on the line 3—3 of Fig. 1.

The body portion of the improved bottle 40 receptacle or cabinet is preferably formed of sheet metal and includes a front wall 1, a rear wall 2, side walls 3 and a bottom 4. By referring to Fig. 2, it will be seen that the bottom constitutes a continuation of the rear 45 wall and is bent upwardly and soldered or otherwise rigidly secured to the front and side walls. A substantially tubular blank is employed when forming the body and is crimped longitudinally, as shown in Fig. 3, 50 to define the walls which are flat and are

joined by front and rear flanges 5 and 6. These flanges are of double thickness and the rear flanges project outwardly beyond the front flanges and are formed with openings 7, as shown in Fig. 1, through which suitable fasteners, such as nails or screws, may be passed to firmly secure the receptacle to a wall, door frame or any other support. By referring to Figs. 1 and 2, it will be seen that the rear wall projects upwardly to form 60 a headboard 8 in which one or more fastener receiving openings 9 are formed and that the upper edges of the side walls slope downwardly from the rear wall to the front wall. The cover 10 is hinged to the rear wall, as 65 shown at 11, and is provided with depending flanges 12 to overhang the front and side walls, a hasp 13 being secured to the front flange and movable into and out of engagement with a keeper or staple 14 which projects from the front wall. A sheet 15 of asbestos or any other suitable insulating material is disposed within the cover and is retained in place by a sheet metal covering 16 70 preferably soldered to the depending flanges 75 of the cover.

The liner which fits within the body is also formed of metal and includes a bottom 17, front and rear walls 18 and 19 and side walls 20. The liner conforms to the contour of the 80 body, as shown in Fig. 3, and its walls have their upper end portions bent outwardly to provide flanges 21 which contact with the front, rear and side walls of the body but are not secured thereto. A sheet 22 of asbestos 85 or any other suitable insulating material is placed in the bottom of the body and other sheets 23 are disposed in the body against the inner surfaces of its walls. These vertically disposed insulating sheets carry metal strips 24 which extend vertically in spaced relation to the sheets of insulation and have their ends bent about the upper and lower edges of the sheets and tightly crimped into engagement therewith, as shown at 25. Since 90 the strips 24 are disposed in spaced relation to the insulating sheets, they will retain the walls of the liner spaced from the insulation and define a dead-air space about the liner 95 which will assist to prevent heat and cold 100

from affecting the temperature of the interior of the receptacle and thereby very effectively prevent milk placed in the receptacle from freezing during cold weather or turning sour during warm weather. It should also be noted that the metal strips will constitute skids and allow the liner to be very easily slid into and out of the body. Each of the side walls of the liner carries a ring 10 so that the liner may be easily drawn outwardly. It will thus be seen that when it is necessary to remove dirt from the liner it can be very easily drawn outwardly and after being thoroughly cleaned replaced.

Having thus described the invention, I claim:

1. An insulated receptacle comprising a body open at its top and having the inner surfaces of its walls uninterrupted throughout 20 its depth, a removable liner for said body spaced from the walls and bottom of the body and having flanges at the upper ends of its walls extending to the walls of the body, sheets of insulating material between the liner 25 and bottom and walls of the body and readily removable when the liner is removed, strips of flat metal carried by the insulation sheets between the walls of the liner and body and extending vertically and bearing against the 30 walls of the liner to retain the liner spaced from the insulation and frictionally hold the liner in place and defining skids to facilitate insertion and removal of the liner, and a cover for said body.

2. An insulated receptacle comprising a body open at its top, a removable liner for said body spaced from the walls and bottom of the body and having flanges at the upper ends of its walls extending to the walls of the body, 35 sheets of insulating material between the liner and bottom and walls of the body, spacing strips carried by insulation sheets between the walls of the liner and body, said strips extending vertically in spaced relation to the 40 sheets with their ends secured thereto and serving to retain the walls of the liner spaced from the insulation and constituting skids to facilitate insertion and removal of the liner.

3. An insulated receptacle comprising a 45 body open at its top, a removable liner for said body spaced from the walls and bottom of the body and having flanges at the upper ends of its walls extending to the walls of the body, sheets of insulating material between the liner and bottom and walls of the body, 50 spacing strips carried by insulation sheets between the walls of the liner and body, said strips extending vertically in spaced relation to the sheets with their ends crimped 55 about the upper and lower marginal portions of the sheets and serving to retain the walls of the liner in spaced relation to the insulation to define dead-air spaces and constituting skids to facilitate insertion and removal of 60 the liner.

4. A receptacle comprising a body consisting of a tubular member bent longitudinally to form front, rear and side walls and flanges connecting the walls and projecting transversely therefrom, the rear wall having an extended lower portion bent forwardly and joined to the front and side walls to provide a bottom for the body. 70

5. A receptacle comprising a body consisting of a tubular member bent longitudinally to form front, rear and side walls and flanges connecting the walls and projecting transversely therefrom, the rear wall having an extended lower portion bent forwardly and joined to the front and side walls to provide a bottom for the body, the rear wall being of greater dimensions than the front wall and the flanges connecting it with the side walls projecting outwardly beyond the front flanges and having fastener receiving openings 85 formed therein. 75

In testimony whereof I affix my signature.
